(57) **CLAIM**

The ornamental design for an epidural catheter fixation device, as shown.

DESCRIPTION

FIG. 1 is a top plan view of an epidural catheter fixation device, in accordance with our new design;

FIG. 2 is a side elevational view of the epidural catheter fixation device of FIG. 1, taken from the bottom of FIG. 1;

FIG. 3 is a side elevational view of the epidural catheter fixation device of FIG. 1, taken from the top of FIG. 1;

FIG. 4 is a front elevational view of the epidural catheter fixation device of FIG. 1, taken from the left side of FIG. 1;

FIG. 5 is a rear elevational view of the epidural catheter fixation device of FIG. 1, taken from the right side of FIG. 1; and,

FIG. 6 is a bottom plan view of the epidural catheter fixation device of FIG. 1.
